Patented Oct. 31, 1922.

UNITED STATES PATENT OFFICE.

FRIEDRICH W. MEYER, OF MILWAUKEE, WISCONSIN, ASSIGNOR TO THE CUTLER-HAMMER MFG. CO., OF MILWAUKEE, WISCONSIN, A CORPORATION OF WISCONSIN.

CONTROL MEANS FOR ELECTROMAGNETIC HAMMERS AND THE LIKE.

Application filed March 18, 1918. Serial No. 223,199.

To all whom it may concern:

Be it known that I, FRIEDRICH W. MEYER, a citizen of the German Empire, residing at Milwaukee, in the county of Milwaukee and State of Wisconsin, have invented new and useful Improvements in Control Means for Electromagnetic Hammers and the like, of which the following is a full, clear, concise, and exact description, reference being had to the accompanying drawing, forming a part of this specification.

This invention relates to control means for electromagnetic hammers and other reciprocating devices.

In practice it has been found that the self induction of the operating magnets of electromagnetic hammers and the like tends to materially curtail the efficiency thereof and the present invention has among its objects to provide control apparatus which will minimize the self inductive effects of such devices and provide for a substantial increase in the efficiency thereof.

A further object is to provide control apparatus which will enable operation of the controlled device on either alternating or direct current.

Other objects and advantages of the invention will hereinafter appear.

The accompanying drawing illustrates certain embodiments of the invention and the same will now be described, it being understood that the invention is susceptible of various modifications.

In the drawing, Figure 1 shows diagrammatically control apparatus for a device supplied from an alternating current circuit.

Fig. 2 shows diagrammatically apparatus for controlling a device supplied from a direct current circuit; and,

Figs. 3 and 4 show certain curves herein-after explained.

Referring to Fig. 1, the same shows an electromagnetic hammer of conventional form which briefly described comprises a casing 1 having a central tubular portion 2, a tool 3 reciprocably mounted in said tubular portion, an electromagnetic winding 4 surrounding said tubular portion and a pivoted armature 5 to be attracted against the action of a spring 6 for imparting blows to the tool 3. And here it may be noted that if

such a hammer be supplied as in the past, with an alternating current of sine wave form by a dynamo provided with slip rings to complete circuit during one cycle and to interrupt circuit during the succeeding one or two cycles, the self induction of said hammer will curtail the force of its blows as depicted in Fig. 3. In said figure *e* represents the electromotive force curve of sine form, *i* the current curve which tends to follow the electromotive force curve but which drops off abruptly upon attraction of the armature and *B* the consequent magnetic field curve. Thus the maximum energy or induction is available for only a small fraction of each stroke of the hammer with a consequent curtailment of the force of its blows. On the other hand, a magnetic field such as depicted in Fig. 3, heats the hammer to practically the same degree as would a magnetic field of constant value throughout each stroke since the heating is mainly due to hysteresis losses in the iron which are directly proportional to the maximum induction per cycle and the control means now to be described provides for increasing the efficiency of the hammer by increasing the duration of maximum induction during each stroke.

Such control means comprises a transformer *T*, an electroionic device *7*, a small alternating current generator *G* and batteries *8* and *9*. The transformer *T* has a primary comprising delta connected windings 10, supplied by a three phase circuit *L* and a secondary comprising star connected windings 12, 13, 14, 15, 16 and 17 to produce a six phase current. The electroionic device *7* is provided with anodes 18, 19, 20, 21, 22 and 23, each connected to one of the secondary coils of transformer *T* and with a cathode 24 heated by current from battery *9* and connected by conductor 25 to one terminal of the hammer winding which has its other terminal connected by conductor 26 to the star point of the secondary of said transformer. Thus the hammer winding is arranged to be supplied with current by the transformer *T* but only through said electroionic device which inherently functions as a rectifier and discharges under the control of an auxiliary anode or grid 27. The grid 27 is connected to the cathode 24 and the battery *8* and gen-

erator G are included in circuit therebetween, the battery to supply a positive potential to the grid and the latter to intermittently oppose the battery potential. As shown, the 5 generator is provided with a pair of slip rings 28 and 29, the former being half insulated to relieve the grid cathode circuit of the non-opposing potential waves. Thus the electroionic device will function 10 under the control of the generator G to supply an intermittent pulsatory current to the hammer winding and obviously the generator may be designed for any desired time interval between successive pulses. Also the 15 generator may be designed to supply an electromotive force of any desired wave form whereby the electroionic device, due to its relay effect, may be caused to produce for example, E. M. F., current and induction 20 curves such as illustrated in Fig. 4 wherein e designates the E. M. F. curve, i the current curve and B the induction curve. And with such curves maximum induction is quickly obtained at the commencement of 25 each stroke and maintained until the stroke is practically completed with a consequent material increase in efficiency. On the other hand different curves may be readily obtained by influencing the sensitive circuit 30 of the electroionic device in other ways. Moreover the generator affords control of the number of blows imparted by the hammer per unit of time since the frequency of the current pulses supplied to the hammer 35 may be varied by merely varying the speed of said generator.

Referring to Fig. 2, the same shows schematically a modified electromagnetic hammer comprising a magnetic frame 30, a 40 tool 31 reciprocable therein, an armature member 32 attached to said tool and electromagnetic windings 33 and 34 to attract said armature member in opposite directions. The winding 33 is arranged to attract the 45 armature member for causing the tool to impart blows while the winding 34 is arranged to attract the armature member for retraction of the tool, thus functioning as the spring 6 of Fig. 1. Also, this figure 50 shows a direct current supply circuit L' and electroionic control means for both windings.

The control means comprises an electroionic device 35, batteries 36, 37 and 38 and an alternating current generator G1. The 55 electroionic device comprises a single cathode 39 heated by current delivered by battery 36, two anodes 40 and 41 arranged on opposite sides of said cathode and two auxiliary anodes or grids 42 and 43 each interposed between one of said anodes and said cathode. The cathode 39 is connected by 60 conductor 44 to one side of the supply circuit, and anode 40 is connected by conductor 45 through the hammer winding 33 by con-

ductor 46 to the other side of said supply circuit, while anode 41 is connected by conductor 47 through hammer winding 34 by conductor 48 to the same side of said circuit. Thus provision is made for supplying current to the winding 33 when the electroionic device discharges between anode 40 and the cathode and for supplying current to the winding 34 when said device discharges between anode 41 and the cathode. However, the device is designed to discharge only when given positive potentials are impressed upon its grids by the batteries 37 and 38 subject to control by the generator G1 which opposes the potentials of said batteries. The 70 generator in this instance has a continuous slip ring 49 connected to the cathode and half insulated slip rings 50 and 51 which are respectively connected to the grids 42 and 43 through batteries 37 and 38 respectively. 75 And the slip ring arrangement is such that the potential half waves supplied by the generator oppose the potentials of batteries 37 and 38 alternately for causing the grids to be alternately subjected to positive potentials. 80

Thus in operation the electroionic device will first discharge between one anode and the cathode and then between the other anode and the cathode thereby energizing the hammer windings alternately. And said electroionic device will function as previously described to insure substantially rectangular induction curves for the hammer windings for a high degree of efficiency 95 thereof. Moreover, as in the previous instance, the generator may be designed to afford the desired periods for reverse strokes of the hammer and may be varied in speed to vary the number of strokes of the hammer 100 per unit of time.

What I claim as new and desire to secure by Letters Patent is:

1. The combination with an electromagnetic reciprocating device, of electroionic means in circuit therewith and including regulable means for controlling the instantaneous values of E. M. F. impressed on said device to increase the effective value of the magnetic field of said reciprocating 115 device for a given amplitude thereof.

2. The combination with an electromagnetic reciprocating device, of means for supplying an intermittent pulsatory current to said device, said means including regulable 120 electroionic means through which such current is passed to said device for control of the form of the magnetic field curve of said device.

3. The combination with an electromagnetic reciprocating device having an iron clad magnetic circuit, of means for supplying an intermittent pulsatory current to said device, said means including regulable means controlling the instantaneous values 125 130

of E. M. F. impressed on said device to render the magnetic field curves thereof substantially rectangular.

4. The combination with an electromagnetic reciprocating device, of means to supply an intermittent pulsatory current to said device, said means including regulable electroionic means controlling the instantaneous values of E. M. F. impressed on said device to render the magnetic field curves thereof substantially rectangular.

5. The combination with an electromagnetic reciprocating device, of a supply circuit therefor and electroionic means controlling the current supplied to the operating winding of said device to render the same of an intermittent pulsatory character, said means being regulable to vary the E. M. F. curves of the current pulses supplied thereby to said device.

6. The combination with an electromagnetic reciprocating device, of a supply circuit therefor, electroionic means controlling the current supplied to the operating winding of said device to render the same of an intermittent pulsatory character and means controlling said electroionic means to vary the E. M. F. curves of the current pulses supplied to said device through said electro-

30 ionic means.

7. The combination with an electromagnetic reciprocating device, of an electroionic device in circuit with the operating winding thereof, said electroionic device

having a sensitive circuit and means for supplying an intermittent E. M. F. to said sensitive circuit.

8. The combination with an electromagnetic reciprocating device, of an electroionic device in circuit with the operating winding thereof, said electroionic device having a sensitive circuit and means for impressing an intermittent E. M. F. on said sensitive circuit and varying the frequency of such E. M. F.

45 9. The combination with an electromagnetic reciprocating device, of a supply circuit therefor, an electroionic device connected between the operating winding of said reciprocating device and said supply circuit and means controlling said electroionic device to effect an intermittent discharge thereof and to control the wave shape of the pulses of current passed to said winding.

10. The combination with an electromagnetic reciprocating device, of a supply circuit therefor, an electroionic device connected between the operating winding of said electromagnetic device and said supply circuit and an alternating current generator controlling said electroionic device to effect an intermittent discharge thereof and for controlling the wave shape of the pulses of current passed thereby.

In witness whereof, I have hereunto subscribed my name.

Dr. FRIEDRICH WILHELM MEYER.
